UNITED STATES PATENT OFFICE.

WILLIAM M. McCARTHY, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,088,831.

Specification of Letters Patent.

Patented Mar. 3, 1914.

Application filed October 27, 1906. Serial No. 340,907.

To all whom it may concern:

Be it known that I, WILLIAM M. McCARTHY, a citizen of the United States, residing at Dayton, in the county of Montgomery and State of Ohio, have invented certain new and useful Improvements in Cash-Registers, of which I declare the following to be a full, clear, and exact description.

This invention relates to improvements in cash registers and more particularly to that class of machines provided with a plurality of cash receptacles.

The principal object of this invention is to employ a series of manipulative devices for opening any desired one of a plurality of cash receptacles upon the movement of its respective manipulative device.

Another object of this invention is an improvement in latching devices for the setting elements of the machine.

Another object of this invention is to employ a flash for concealing the indicators until the machine is properly operated.

With these and incidental objects in view, the invention consists in certain novel features of construction and combination of parts, the essential elements of which are set forth in appended claims and a preferred form of embodiment of which is hereinafter specifically described with reference to the drawings which accompany and form part of this specification.

Of said drawings: Figure 1 represents a vertical transverse section of the machine with the indicators and a part of the cash receptacles omitted. Fig. 2 represents a similar section looking in the opposite direction with all of the cash receptacles omitted. Fig. 3 represents an end elevation of the machine showing the printing mechanism. Fig. 4 represents a detail side view partly in section of the gearing for operating the printing platen. Fig. 5 represents a detail side elevation of the clerks' key bank and the operating handle of the machine; and Fig. 6 represents a rear elevation of the drawer plungers and their operating levers.

While this invention is shown as applied to a type of machine shown and described in British Letters Patent No. 4543 of 1903 granted to H. S. Hallwood, it may with

equal facility be applied to any of the well known makes of machine now upon the market.

55

The operating handle 1 is made fast to a central transverse shaft 2 around which is coiled a stout spring 3, one end of which abuts against a horizontal rod 4 and the other end rests upon the top of an arm 5 pivoted to a rearwardly extending portion 6 of the operating handle 1. Yokes 7 which are pivoted upon the shafts 2 and 8, the latter being mounted in the same plane as the former, rest upon the arm 5. A spring 9 is interposed between an ear 10 projecting from said arm, and a stud 11 mounted upon the rearwardly extending portion 6 of the handle 1, so as to absorb any shock given to the yokes by a violent operation of the handle. One end of each yoke is attached to a step frame 12 which is controlled by its respective series of keys, while the other ends of said yokes extend through the right hand side frame of the machine and have 75 pinned to them type carriers 13 which are loosely mounted upon a continuation of the shaft 2.

70

The rearwardly extending arm of each step frame (Fig. 2) to which is attached its 80 respective yoke, is provided with a pin 14 which plays in an elongated slot 15 of a link 16. The upper end of each link 16 is connected to one end of an arm 17, the other end of said arm being provided with a segmental rack 18 which meshes with a pinion 19 fast to an indicator 20 mounted upon a shaft 21. The arm 17 is loosely mounted upon a shaft 22 around which is coiled a spring 23, one end of which bears upon the 90 arm 17 and the other end is fastened to the shaft thereby tending to hold the indicator in the position shown. Attached to each pinion 19 is a star wheel 24 which is engaged by an alining pawl 25. These alining pawls, of which there is one for each star wheel, are rocked out of and into engagement with said star wheels by means not shown here but which are fully shown and described in the aforementioned patent. 100

95

The operating handle is latched in the position shown in Fig. 1 by a pawl 26 which engages a pin 27 formed on said handle, the pawl being held in such engagement by

a light spring 28 coiled about a stub shaft 29 which acts as a fulcrum for said pawl. A laterally projecting pin 30 extends from said pawl 26 and is arranged to be engaged by the upper end of a pivoted arm 31, the lower end of said arm being provided with an anti-friction roller 32 which extends into the path of a depending arm 33 of a detent plate 34 (Fig. 5) which is loosely mounted upon the shaft 8. The upper end of the arm 31 is held in contact with the pin 30 by a very light coil spring 35.

The detent plate 34 at its forward edge is provided with a series of hook fingers 36 which have blunt ends 37 with the exception of the lowermost finger which is rounded and slightly longer than the rest. The eight upper keys 40 are clerks' keys and the bottom key 41 is a release key. Upon depressing one of the clerks' keys its laterally extending pin 42 will contact with a plate 43, which is pivotally mounted upon a transverse shaft 44, and rock said plate rearwardly carrying a shoulder 45 formed thereon from under a pin 46 projecting from the detent plate 34, allowing said plate 34 to be drawn downwardly by spring 47 until the bottom finger contacts with the laterally projecting pin 48 of the release key 41. This movement of the plate 34 is sufficient to latch the operated key in its depressed position by its respective hook finger 36 and the remainder of the clerks' keys in their outermost position by the blunt ends 37 of the rest of the hook fingers passing under the pins 42. This limited movement of the plate 34 brings its depending arm 33 against the roller 32 projecting from the arm 31. Now upon depressing the release key 41 the plate 34 will be given an additional movement by the spring 47 thereby rocking the arm 31, which will in turn disengage the pawl 26 from the pin 27 of the handle 1 allowing the handle to be operated by its spring 3. As the handle 1 moves upwardly and rearwardly the part 6 moves downwardly and forwardly. The lower end of the part 6 (Fig. 1) is provided with an elongated slot 49 which straddles a rod 50 mounted within a slide 51 which in turn is mounted upon two rods 52 (only one being shown) that extend from the front to the rear of the machine and which are supported at their ends by lugs 53 extending up from the base.

The slide 51 is equipped with an anti-friction roller 54 which, when the slide is carried forward, contacts with the under incline side of a pawl 55 pivoted to a lever 56 and elevates the free end of said pawl. Upon the return of the slide to its normal position the roller 54 rides upon the upper incline side of the pawl and depresses same, the pawl being limited in its downward movement by a pin 57 on the lever 56 car-

ries the latter with it. This lever is pivoted to the frame of the machine at 58 and is provided with a forwardly extending arm 59 which lies under a frame 60 pivoted upon the shaft 44. As the rear end of the lever 56 is depressed as above described the forward extension 59 of the lever will rock the frame 60 which will return the detent plate 34, by means of its depending arm 33, to its normal position thereby allowing the keys 40, 41 and the plate 43 to return to their home position through suitable springs (not shown). The above described frame 60 also releases the detent frames of the amount key banks. As the roller 54 passes off the upper side of the pawl 55 the parts actuated through the means of said roller are returned to their normal position by a spring 61 coiled about the shaft 44, one end being fastened to said shaft and the other end bearing on the upper portion of the frame 60. The latter is limited in its downward movement by an extension 62 of said frame contacting with the base of the machine, while the lever 56 is limited in its upward movement by a flange 63 formed thereon coming in contact with the roller 54.

The step frames 12 and the type carriers 13 connected to the yokes 7 are controlled by the clerks' keys 40 and the amount keys 64. Resting upon the three outermost yokes 7, which are controlled by the amount keys, are depending arms 65 of levers 66. It will be seen, as the yokes drop to a position determined by the amount keys depressed, they will be followed by the levers 66. These levers carry pawls 67 which when the levers are returned to their normal position, by the operating handle, will register upon the adding wheels 68 the sum represented by the keys depressed.

Just before the yokes 7 start to descend the alining pawls 25 are rocked out of engagement with the star wheels 24, allowing the indicators to be rotated to a position to indicate the amount represented by the operated keys. As the handle 1 commences its downward movement to return the yokes to their normal position the pawls 25 are rocked into engagement with the star wheels 110 to lock the indicators in their adjusted position, while the elongated slots 15 in links 16 allow the yokes to be returned, all of which is fully shown and described in the aforementioned patent.

The shaft 2 to which is fastened the operating handle 1 has also secured to it a segmental rack 67 (Figs. 3 and 4) which meshes with a pinion 68 loosely mounted upon a sleeve 69 which in turn rotates about a shaft 70. This pinion carries a pawl 71 spring pressed into engagement with a raised portion 72 of the sleeve 69. As the segment 67 is oscillated upon each operation of the machine the pinion 68 is given a complete revo-

lution in both directions; when moving in the direction of the arrow in Fig. 4 the pawl rides idly about the sleeve 69, but when moving in the opposite direction the pawl 5 engages the nose 72 and rotates the sleeve 69.

A cam 73 is carried by the sleeve 69, and as said sleeve is rotated forces the platen 74 against the type carriers 13 thereby making an impression upon the record strip 75 10 which is fed over said platen in any suitable manner. Any of the well known forms of inking devices may be employed to ink the type.

Referring now to Fig. 1 it will be seen 15 that the laterally extending pins 42 of the clerks' keys 40 engage inclined slots 75^a formed in the forward ends of a series of bell-crank levers 76, which are pivoted upon the shaft 8. The downwardly extending 20 ends of said levers are bent at different angles so as to bring them into engagement with their respective drawer plunger operating arms 77 (Fig. 6). Each of the downward ends of the bell-crank 76 is provided 25 with an elongated cam slot 78 which straddles a pin 79 mounted upon its respective arm 77, the latter being pivoted upon a transverse shaft 80. The rear ends of the arms 77 are provided with enlarged slots 30 81, in the bottoms of which rest pins 82 of the drawer plungers 83. These plungers pass downwardly through the casing of the machine and engage with latches 84 secured to the rear of the cash drawers 84^a and hold 35 the same in their innermost position against the tension of springs 85. The enlarged slots 81 and the arms 71 permit of an independent movement of the drawer plungers upon the closing of the cash drawers.

40 The plate 43, (Figs. 2 and 5) is provided at its upper end with a wiper pawl 86, which engages a flange 87 on the lower end of a bell crank lever 87^a, when any of the clerks' keys or the release key is operated, 45 and rocks the upper hook end of said lever out of engagement with a pin 88 mounted on an arm 89 supporting flashes 90 which are immediately drawn to concealing position by spring 91. A pin 92 on the side 50 frame (Fig. 3) limits the movement of the flashes in one direction. The wiper pawl 86 passes over the flange 87 immediately after the bell-crank 87^a is rocked sufficiently to release the flash arm 89 and the said bell-crank is carried back to its normal position 55 against a pin 87^b, by a light coil spring 87^c. Upon the return of the plate 43 the pawl 86 trips idly by the flange 87. Pivoted to the right hand end supporting arm 89 is a link 60 93, the lower end of which is provided with a roller 94. This roller when drawn to its upper position by the release of the flash arm 89 is arranged to be engaged by a camming projection 95 secured to a forward 65 extension of an arm 96 fastened to the rock

shaft 2, when the latter is rotated in a rearward direction upon the operation of the release key 41, and thereby return the link 93 and flashes 90 to the position shown in Fig. 3. The link 93 is guided in its movements 70 by an elongated slot 93^a formed therein straddling a shaft 93^b.

It will be seen from the above description that upon depressing any one of the clerks' keys its corresponding cash drawer will be 75 opened and the indication concealed, entirely independent of the operation of the machine.

If it were not for the flash mechanism a dishonest clerk could manipulate the machine, if he had two successive sales of the same amount, by simply depressing his key for the second operation which would release his drawer but would not destroy the previous indication; the customer seeing the clerk's drawer opened and the correct amount of the purchase displayed upon the indicators would think the machine had been properly operated, whereas all the clerk had done was to simply release his cash drawer.

It is to be understood that while the release key is shown as mounted in the same bank as the clerks' keys, it does not release any of the cash drawers nor control the movement of the clerks' graduated step frame.

With a register as above described it will be seen that if any discrepancy occurs between the amount shown on the adding wheels and that in the cash drawers, it can be easily traced by means of the record strip upon which is recorded the initial of the clerk as well as the amount of each transaction.

While the form of mechanism here shown and described is admirably adapted to fulfil the objects primarily stated, it is to be understood that the invention is not confined to any form of embodiment of the invention here disclosed, for it is susceptible of embodiment in various forms all coming within the scope of the claims which follow.

What is claimed is as follows:

1. In a cash register, the combination with a plurality of keys and a plurality of cash receptacles, of connecting means from each key for releasing the corresponding receptacle, a special key, a detent mechanism common to all of said keys, an operating mechanism for the register, a lock for said mechanism controlled by said detent, said detent being so constructed as to require an operation of the special key after one of said releasing keys has been depressed.

2. In a cash register, the combination with a plurality of keys, and a corresponding number of cash receptacles, of means normally locking each receptacle, means operated by the keys for releasing the locking

- means for the corresponding receptacle, an operating mechanism, a lock for said mechanism, a special key for releasing said lock and a detent common to all said keys.
5. In a cash register, the combination with a plurality of initial keys and a special key, of detent means common to said keys, an operating mechanism normally locked, but released by operating said special key which 10 gives a full movement of said detent, the construction of said detent being such that a partial movement thereof sufficient to lock the initial keys occurs when any initial key is operated, a plurality of cash receptacles 15 with separate means for latching each receptacle, and connections from each initial key to unlock one of the receptacles.
6. In a cash register, the combination with a plurality of keys, a corresponding number 20 of cash receptacles, latching means for each receptacle operated by the keys, a special key, a detent common to all of said keys, said detent being so constructed as to require an operation of the special key after 25 one of said operating keys has been operated, an indicator, an operating mechanism, controlled by said detent, a shield for the indicator moved to concealing position when said detent is operated, and means controlled 30 by the operating mechanism for moving the shield to exposing position.
7. In a cash register, the combination with a plurality of initial keys, of a plurality of cash safes each having a movable part, latching 35 means for the movable parts, connections whereby the actuation of a key operates the latching device for one of the movable parts, a special key, detent mechanism so constructed as to require an operation 40 of the special key after one of said initial keys has been operated, an indicator, a shield for said indicator, normally in exposing position and adapted to be moved to concealing position upon an operation of 45 said detent, an operating mechanism controlled by said detent and means controlled by the operating mechanism for moving the shield to exposing position.
8. In a cash register, the combination with 50 a plurality of keys and a corresponding number of cash receptacles, of means for releasing any receptacle by the actuation of the proper key, a special key, a detent common to all of said keys, an operating mechanism for the machine controlled by the special key, and means controlled by said mechanism for releasing the key detent.
9. In a cash register, the combination with 55 manipulative devices, of cash safes having movable parts, means operated by said devices for releasing a desired movable part, a special manipulative device, a common means for retaining said devices in operated position, an operating mechanism for the 60 machine controlled by the special manipu-

lative device, and means controlled by said mechanism for releasing said retaining means.

8. In a cash register, the combination with a plurality of manipulative devices, of a plurality of cash safes having movable parts normally in concealing position but released by the actuation of the manipulative devices, a special manipulative device, detent mechanism for all of said manipulative devices and so constructed as to require an operation of the special manipulative devices after one of said first mentioned manipulative devices has been operated, an indicator, a shield for the same released and allowed to move to concealing position by the actuation of said detent, and an operating mechanism for the machine controlled by the latter and serving to return said shield to normal exposing position. 75

9. In a cash register, the combination with a plurality of manipulative devices and a plurality of cash safes having movable parts, separate latching means for each movable part, means connecting each manipulative device to the corresponding latching means so that the actuation of a device moves the latching means to releasing position and retains it, a special manipulative device, an operating mechanism for the machine controlled by the latter, a detent common to all of said manipulative devices, and means actuated by said operating mechanism for releasing said detent to allow the manipulative device and the latching means 90 to return to normal position. 95

10. In a cash register, the combination with accounting devices, of oscillatory actuating elements therefor, keys for limiting the movement of the actuating elements in one direction, a normally locked operating mechanism arranged when released to automatically move with the actuating elements and to be manually operated to return the elements in the opposite direction, a special key for releasing the operating mechanism, a plurality of initial keys and a corresponding number of cash receptacles, and a common locking means for said special and initial keys. 105

11. In a cash register, the combination with a plurality of keys and a corresponding number of cash receptacles, latching means for the receptacles operated by said keys, a normally locked operating mechanism for the register and means operated independently of the afore-mentioned keys for releasing the operating mechanism and locking the keys from operation. 110

12. In a cash register, the combination with a plurality of keys and a corresponding number of cash receptacles, latching means for the receptacles controlled by said keys, a normally locked operating mechanism for the register and means operated independently of the afore-mentioned keys for releasing the operating mechanism and locking the keys from operation. 125

130

ently of the afore-mentioned keys for releasing the operating mechanism and locking the keys from operation.

13. In a cash register, the combination with a plurality of keys and a corresponding number of cash receptacles, latching means for the receptacles controlled by said keys, a normally locked operating mechanism for the register, and means controlled by a special key for releasing the operating mechanism, and locking the first mentioned keys from operation.

14. In a cash register, the combination with a plurality of keys arranged to be operated in a certain sequence, and a common latching means for said keys constructed to lock the unoperated keys from operation when the sequence of operation is varied.

15. In a machine of the class described, the combination with a series of depressible keys, and a member differentially movable for the purpose of latching a plurality of said keys in depressed positions.

16. In a machine of the class described, the combination with a series of depressible keys, and a detent differentially movable for the purpose of latching a plurality of said keys when they are successively operated.

17. In a cash register, the combination with a plurality of manipulative devices arranged to be operated in a certain sequence, of a detaining device common to all of said manipulative devices constructed to

render inoperative the unoperated manipulative devices when the sequence is varied. 35

18. In a cash register, the combination with a plurality of manipulative devices, of a detaining device common thereto constructed so as to detain successively operated manipulative devices without releasing those previously operated. 40

19. In a cash register, the combination with a plurality of keys, of a single detent plate therefor constructed so as to latch successively operated keys without releasing those previously operated. 45

20. In a cash register, the combination with a plurality of keys arranged to be operated in a certain sequence, of a latching means common to said keys constructed to lock the unoperated keys from operation when the sequence is varied, and means controlled by the keys normally holding the latching means in an inoperative position. 50

21. In a cash register, the combination with a plurality of keys, of a differentially movable latching means common to said keys, and means, also common to said keys, normally holding the latching means in an inoperative position. 55

In testimony whereof I affix my signature in the presence of two witnesses.

WILLIAM M. McCARTHY.
